DESIGN.

—o—
F. MANKEY.

OPENWORK PANEL.

No. 18,452.

Patented July 10, 1888.

UNITED STATES PATENT OFFICE.

FREDERICK MANKEY, OF WILLIAMSPORT, PENNSYLVANIA.

DESIGN FOR AN OPEN-WORK PANEL.

SPECIFICATION forming part of Design No. 18,452, dated July 10, 1888.

Application filed February 28, 1887. Serial No. 229,267. Term of patent 7 years.

To all whom it may concern:

Be it known that I, FREDERICK MANKEY, of Williamsport, Lycoming county, Pennsylvania, have invented and produced a new and original Design for Open-Work Panels, of which the following is a specification, reference being had to the accompanying photograph, forming part hereof.

My design consists in the open work panel, substantially as herein shown and described.

The edges on two opposite sides of each opening show each two curves meeting, as A B and C D. The edges of each of the other sides of each opening show an inwardly-curved por-

tion, E, straight portions F, and straight portions G at right angles to said straight portions F. The curved portions A B C D are adjacent to the straight portions F. The said openings are in regular rows in the panel. Upon the face of the panel and between the openings appear short beads H.

I claim—

The design for an open-work panel, substantially as herein shown and described.

FREDERICK MANKEY.
